TORSION BAR CHAIR IRON

Finn Lie, Ring Station, near Hamar, Norway
Filed Aug. 17, 1961, Ser. No. 132,037
6 Claims. (Cl. 248—373)

This invention relates to chair irons for tilting chairs, as for example office chairs, and more particularly this invention relates to a tiltable chair iron wherein a simplified torsion bar construction is utilized to resiliently restrain the backward tilting of a chair seat and back as a person, sitting in the chair, shifts his weight to tilt the seat and back in a rearward manner, and wherein the chair seat absorbs the torque of the torsion bar.

A number of tilting chair iron constructions have heretofore been developed which comprise as a part of their mechanism, telescopic tubes which rotate relative to each other, and also a torsion bar within the inner telescopic tube to provide a resilient restraining force against movement of a chair seat. While the telescopic tube structure provide tilting chair mechanisms of substantial durability and long life, their costs of manufacture are increased by the necessary telescopic tubes and the labor involved in assembly and joining these parts.

In addition to the steps forward in the art provided by the telescopic tube torsion bar assemblies over the prior art chair iron constructions utilizing heavy castings and coil springs, a further advance in the seating art would be provided if the telescopic tubes of torsion bar structures could be eliminated, thereby further simplifying the structure and reducing the cost of manufacture of tilting chair iron constructions.

Accordingly it is an important object of the present invention to provide a novel, tiltable chair iron utilizing a torsion bar to provide a resilient restraining force for the tilting movement of the chair seat, as a neat, precise and compact unit of simplified construction.

Another object is to provide a tiltable chair iron, utilizing the torsion bar principle, which is of improved, simplified construction and is readily assembled with a minimum amount of labor, and that has long life substantially free of maintenance.

A further object is to provide a tiltable chair iron utilizing a torsion bar wherein the chair seat frame absorbs the torque from the torsion bar.

A further object is to provide a tiltable chair iron utilizing a torsion bar wherein a chair seat frame bracket engages spaced stop members carried by a torsion bar support tube bracket to establish the limits of pivotal movement of the chair seat.

A still further object is to provide a tiltable chair iron utilizing the torsion bar principle wherein a simple tensioning arm of neat appearance is interposed between one end of the torsion bar and a chair seat frame bracket to provide adjustment of the tension of the torsion bar and thereby adapt the chair to use by occupants of differing weights.

A still further object is to provide a tiltable chair iron using a torsion bar without the requirement of telescopic tubes in its structure as heretofore used, thus providing a novel tiltable chair iron construction of simplified configuration and of substantially lower cost.

Other objects of this invention will appear in the following description and appended claims, reference being had to the accompanying drawings forming a part of this specification wherein like reference characters designate corresponding parts in the several views.

In the drawings:

FIGURE 1 is a front elevational view of a chair incorporating a novel, tilting iron of the torsion bar type, made in accordance with the present invention;

2

FIGURE 2 is a top plan view of the novel torsion bar, tilting chair iron of the present invention;

FIGURE 3 is a left end elevational view taken along the line 3—3 of FIGURE 2, looking in the direction of the arrows;

FIGURE 4 is a right end elevational view taken along the line 4—4 of FIGURE 2, looking in the direction of the arrows;

FIGURE 5 is an enlarged fragmentary top plan view of the right hand end of the support tube, showing the assembly of the stop-carrying bracket thereto;

FIGURE 6 is an end elevational view taken along the line 6—6 of FIGURE 5;

FIGURE 7 is an enlarged fragmentary exploded top plan view showing the manner in which the right hand seat frame bracket is mounted for pivotal movement within the right hand end of the support tube;

FIGURE 8 is an enlarged right end elevational view taken along the line 8—8 of FIGURE 7, and looking in the direction of the arrows; and

FIGURE 9 is an enlarged fragmentary exploded top plan view showing the assembly of the right hand end of the iron of FIGURE 2, with the torsion bar within the support tube and extending through the right hand seat frame bracket to connect with the adjusting lever.

Before explaining the present invention in detail it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

Brief Perspective

Briefly the present invention relates to a novel tilting chair iron of the torsion bar type wherein a main support tube pivotally supports a pair of chair seat frame brackets. A torsion bar is positioned within the support tube and is connected at one end to the support tube. The torsion bar extends out of the other end of the support tube for connection to one end of an adjusting handle that is restrainingly engageable at the other end to one of the chair seat frame brackets.

In accordance with this simplified and improved structure of the present invention, the chair seat frame absorbs the torque from the torsion bar.

A yoke of simplified configuration is joined to the support tube intermediate its length and is provided with a spindle hole to receive the upper end of the spindle provided in a chair base, whereby the iron and the seat carried thereby are supported for pivotal movement upon a chair base.

Thus, pivoting of the chair seat about the support tube is resiliently restrained by the torsion bar; the chair seat frame absorbs the restraining force of the torsion bar; and the seat is restrained within limits of pivotal movement by engagement of one of the seat frame brackets with stops carried by the support tube of the iron.

The Environment

As shown in FIGURE 1, a chair structure utilizing a torsion bar iron of the present invention includes a floor-engaging base 10 having outwardly extending legs 12 supported at their lower terminal ends by rollers 14 for moving the chair over a supporting surface. Centrally of the base 10 there is provided a vertically disposed spindle 16 having an exposed upper end, suitably of tapered configuration (not shown). The upper end of the spindle 16 projects into a spindle hole 18, FIGURE 2, formed in

a yoke 20 that supports the chair iron 22 of the present invention. A chair seat 24, FIGURE 1, is mounted upon the iron 22 for rearward pivotal movement against resiliently restraining forces imparted by a torsion bar, to be subsequently described, which forms a component part of the iron. Chair arms 26 and a back 28 of suitable configuration are mounted on the seat 24 in a conventional manner to complete the chair structure.

The Novel Iron

As shown in FIGURE 2, the chair iron structure centers around a support tube 30 that is secured to and carried by the aforementioned yoke 20. The yoke 20 is suitably made of a stamping of generally U-shaped configuration, having a bight portion 32 to the ends of which are integrally joined upstanding arms 34. The previously mentioned spindle hole 18 is formed centrally of the bight portion 32.

The upstanding arms 34 of the yoke 20 are provided with aligned apertures through which the support tube 30 is inserted and then the parts are suitably joined as by welding as at 36. It will be noted that the yoke 20 is positioned centrally of the support tube 30 so that the weight of the chair above the iron 22 will be equally balanced on each side of the spindle hole 18 when the spindle 16 is inserted therein.

The frame of the chair seat is pivotally mounted upon the support tube 30 by connection at the left end to a bracket 38 and at the right end to a bracket 40. As shown in the end elevational view of FIGURE 3, the bracket 38 comprises a vertically disposed wall 42 of triangular configuration with the base of the triangle in the form of a horizontally disposed elongated plate 44. It will be seen from the foregoing description that the bracket 38 is suitably stamped from angle iron.

As shown in FIGURE 2, each end of the plate 44 of bracket 38 is provided with a suitable aperture 46 through which bolts or other suitable fastening devices (not shown) can be passed for connection with the frame of the chair seat 24, previously mentioned above in the description relating to FIGURE 1.

At the lower apex of the vertically disposed wall 42 of the bracket 38, a bearing 48 is secured as by welding into a suitable aperture provided in the wall 42. The left end of the support tube 30 is inserted into the bearing 48 and thus the bracket 38 is rotatably mounted upon the left end of the tube 30. A small amount of lubricant is applied between the bearing 38 and tube 30 to facilitate rotation and provide long life.

As best shown in FIGURE 5, the right end of the support tube 30 is fitted with a stop bracket arm 50. As shown in the FIGURE 6, the bracket arm 50 is provided intermediate its length with an aperture 52 into which the right hand end of the support tube 30 is fitted, followed by fastening as for example by welding as at 54.

The Stop Members

Adjacent the front end of the stop bracket arm 50, there is provided a front stop member 56 that, as shown, may be a separate piece of steel welded as at 58. Also, at the rear end of the stop bracket arm 50, there is provided a rear stop member 60 that may be a separate piece, also welded as at 62. In connection with the front and rear stop members 56 and 60, it is to be considered within the scope of the invention to punch them out of the body of the stop bracket arm 50, as will be evident to those skilled in the art of metal working. By so operating, the labor involved in fabricating the present invention would be still further reduced.

As shown in FIGURES 7 and 8, the right hand chair frame support bracket 40 is generally similar in configuration to the left hand chair seat frame bracket 38 and includes a generally triangular vertically disposed wall 64 integrally formed with an elongated and horizontally disposed plate 66 that is provided with apertures 46 adja-

cent each of the ends for attachment of the chair seat frame by bolts or the like as previously mentioned. At the lower apex of the triangular vertical wall 64, an aperture 68 is provided and a tubular bushing 70 is inserted and fixed in position as by welding at 72. The outside diameter of the bushing 70 is slightly smaller than the inside diameter of the support tube 30, FIGURE 7, so that the two parts may interfit in rotatable relation, a small amount of lubricant being applied during assembly to facilitate rotation and provide long life.

By reference to the assembled view of FIGURE 4, it will be noted that the right hand seat frame bracket 40 is restrained in its forward movement by abutment with the front stop member 56 of stop bracket arm 50 and is restrained in its rearward pivotal movement by engagement with the rear stop member 60 of stop bracket arm 50.

The Torsion Bar

By reference to FIGURES 3, 4 and 9 of the drawings, it will be observed that a torsion bar 74 extends coaxially of the support tube 30. At the left end of the chair iron 22, the torsion bar is secured to the support tube 30. This is done by fitting onto the torsion bar, an annular plug 76 that is provided with a centrally disposed square hole for receiving the left end of the torsion bar 74; fastening the plug to the torsion bar as by welding; and also fastening the outer periphery of the plug to the inside wall of the support tube 30 as by welding. Thus the left end of the torsion bar cannot move with respect to the support tube 30.

As shown in FIGURE 9, the right end of the torsion bar extends beyond the stop bracket arm 50 and fits freely through the inner bore of the tubular bushing 70 of right hand seat frame bracket 40. A tension adjusting and contact arm 78 is connected to the right hand end of the torsion bar 74 and is adapted to engage the underside of the horizontal plate 66 of the right hand seat frame bracket 40. The control arm 78 is provided at its forward end with a bushing 80 having an outside diameter slightly less than the inside diameter of the tubular bushing 70 of the bracket 40. The inside of the bushing 80 is provided with a square bore 82 into which the extreme right end of the torsion bar 74 is adapted to fit in snugly engaging relation. A set screw 84 is provided to secure the torsion bar 74 and the control arm 78 relative to each other. An annular thrust surface 86 is provided at the inner end of the bushing 80 to abut the exterior of the wall 64 of bracket 40 whereby the bracket 40 is retained in assembled relationship on the right hand end of the unit. The chair seat frame keeps the other bracket 38 in its properly assembled relationship on the unit. Lubricant is applied to the outside of bushing 80.

The other end of the control arm 78 is provided with a threaded aperture 87. An adjusting handle 88, FIGURE 4, has a threaded portion 90 and the threaded portion is passed through the aperture 87 so that the end of the handle 88 passed through the aperture contacts the underside of the horizontal plate 66 of bracket 40.

By reference to FIGURE 4 it will be observed that the chair seat would be in a horizontal position. However, when the chair seat is tilted backwardly, it is resiliently restrained by torsion bar 74 restraining the tension-adjusting and contact arm 78 against counterclockwise rotation. Thus a resilient, restraining force is imposed against rearward pivotal movement of the chair seat 24 of the chair of FIGURE 1 and the pivotal movement of the chair seat is stopped by abutment of the rear edge of the vertical wall 64 of bracket 40 with the rear stop member 60 of stop bracket arm 50.

Tension Adjustment

By means of the tension-adjusting and contact arm 78, the resilient restraining force provided by the torsion bar 74 can be adjusted. Thus, as shown in FIGURE 4, turning the adjusting handle 88 to move the rear end of the

contact arm 78 toward the horizontal plate 66 will have the effect of reducing the pre-twist imparted to the torsion bar 74 and thus will permit the chair to be tilted with less weight or force. On the other hand, adjusting the handle 88 to pull the rear end of the tension arm 78 downwardly and away from the plate 66 will serve to impart a greater pre-twist to the torsion bar 78 and accordingly a larger weight or force will be required to move the chair seat downwardly in a rearward tilting manner. Thus the iron adapts the chair of which it forms a component part to be used by persons of differing weight.

Extended Scope

Materials of construction which can be used in fabricating the chair iron of the present invention generally include steel, brass, aluminum and similar metals, adapted to be fabricated with sufficient strength into relatively light weight structures.

Although not shown, the bearing 48 supporting the left hand bracket 38 and the bushing 70 carried by the right hand bracket 40 can be lined with nylon or other self-lubricating bearing material so that no extraneous lubricant need be used for the unit during its lifetime. In the construction described, maintenance is limited to the insertion of a few drops of lubricant between the inside of the bearing 48 and the outside of the left end of the tube 30 and the inside of the right end of the tube 30 and the outside of the tubular bushing 70. Similarly, a small amount of lubricant is placed between the bushing 80 of the adjusting handle 78 and the inside of the bushing 70.

Although the support tube 30 has been described above as a tube, it will be obvious that equivalent support structures can be employed within the broad scope of the invention. Thus a hollow support member of box, hexagonal or other cross sectional form could be employed. When so operating, it will be necessary to fit a bushing around the left end of the tube 30 to operate within the bearing member 48 and to fit a suitable bushing inside the right hand end of tube 30 to receive the bushing 70 of right hand chair frame support bracket 40.

Advantages of the Present Invention

From the foregoing, it will be observed that a novel and improved tilting chair iron of the torsion bar type is provided in accordance with the present invention that utilizes a minimum number of simply fabricated parts. The unit is distinguished by long life, ready fabrication with a minimum amount of labor and by the fact that the chair seat frame absorbs the torque of the torsion bar.

The unit of the present invention is readily adapted to mass production methods and its assembly merely comprises the insertion of the tubular bushing 70 of the right hand bracket 40 over the right hand end of the torsion bar 74 and into the support tube 30 followed by application of the tension and adjusting control arm 78 to the right end of the torsion bar 74, followed by tightening of the set screw 84.

The unit is then suitably inverted upon an inverted seat cushion and the right and left brackets are secured to the frame of the cushion. Thereafter, the unit is inverted and placed upon the upper end of the spindle 16 of the chair base 10. Following this simple procedure, the chairs may be packaged and are ready for shipment.

I claim:

1. In a tilting chair iron, a spindle engaging yoke, a support tube fixedly carried by said yoke and having first and second ends, a stop bracket arm fixed on the first end of said support tube, first and second spaced stop members on said stop bracket arm, a torsion bar within said support tube and having first and second ends with the second end connected to said support tube at its second end, a first chair seat frame bracket rotatably journaled on the first end of said support tube, a second chair seat frame bracket rotatably journaled on the second end of said support tube, said torsion bar having

its first end extended through said first chair seat frame bracket in freely rotatable relation, and a tension arm connected at its one first end to the second end of said torsion bar to retain said first chair seat frame bracket on said support tube and having its second end abutting said first chair seat frame bracket.

2. In a tilting chair iron, a generally U-shaped support yoke having a spindle socket adapted to fit upon the spindle of the base of a chair, a hollow, elongated support member having first and second ends and fixedly carried by said yoke, a bracket on the first end of said support member, protruding stop members on said bracket, a torsion bar within said support member and having first and second ends with the second end fixedly connected to said support member adjacent the second end of said support member, a first chair seat frame bracket pivotally mounted within the first end of said support member to alternately contact said protruding stop members in its pivotal movement, a second chair seat frame bracket pivotally mounted adjacent the second end of said hollow, elongated support member, said torsion bar having its first end extending through said first chair seat frame bracket in freely rotatable relationship, a tension arm having a bushing journaled in said first chair seat frame bracket and fixedly connected to the end of said torsion bar to hold said first chair seat frame bracket on said first end of said support member adjacent said bracket, and the other end of said tension arm abutting said first chair seat frame bracket, whereby a chair seat mounted upon said chair seat frame bracket is resiliently restrained against pivotal movement by said torsion bar and the degree of pivotal movement is established by said protruding stop members.

3. In a tilting chair iron, a generally U-shaped yoke having a bight portion and aligned arms, said bight portion having a spindle socket adapted to fit upon the spindle of the base of a chair, a support tube fixedly carried by the arms of said yoke and having first and second ends, a stop bracket arm fixedly secured on the first end of said support tube, two spaced stop members on said bracket arm, a torsion bar within said support tube and having first and second ends with the second end fixedly connected to the second end of said support tube, a first chair seat frame bracket having a bushing rotatably journaled within the first end of said support tube adjacent said stop bracket arm to alternately contact said stop members, a second chair seat frame bracket rotatably journaled on the second end of said support tube, said torsion bar having its first end extended through said first chair seat frame bracket bushing in freely rotatable relation, a tension arm having a bushing on one end journaled within said first chair seat bushing, said torsion bar fitting within said tension arm bushing in non-rotatable relation, means releasably anchoring said tension arm to said torsion bar, and an adjusting handle having a portion threaded through the second end of said tension arm and engageable with said first chair seat frame bracket, whereby a chair seat mounted upon said chair seat frame bracket is resiliently restrained against pivotal movement by said torsion bar, the tension of said torsion bar is adjusted by said adjusting handle, and the degree of pivotal movement of the seat is established by said stop members.

4. In a tilting chair iron, a hollow, elongated support member having first and second ends, means for mounting said support member to a chair base, a stop bracket fixed on the first end of said support member, first and second spaced stop members on said stop bracket arm, a torsion bar having first and second ends and being partially positioned within said elongated support member and having the second end connected to the second end of said support member, a first chair seat frame bracket rotatably journaled within the first end of said hollow, elongated support member, a second chair seat frame bracket rotatably journaled on the second end of

said hollow, elongated support member, said torsion bar having its first end extending through said first chair seat frame bracket in freely rotatable relation, a tensioning arm connected at one end to said first end of said torsion bar and having its other end abutting a rear portion of said first chair seat frame bracket, and adjusting means on said tensioning arm adapted to space the other end of said tensioning arm with respect to said first chair seat frame bracket, whereby a desired degree of pre-twist can be imparted to said torsion bar.

5. In a tilting chair iron,
a spindle yoke,
a tube non-rotatably carried by said yoke and having
first and second ends,
a stop bracket arm secured on the first end of said
tube,
15 first and second spaced stop members on said stop
bracket arm,
a torsion bar within said tube with first and second
ends and with the second end connected to the sec-
ond end of said support tube,
a first chair seat frame bracket rotatably journaled on
20 the first end of said support tube and alternately en-
gageable with said first and second spaced stop mem-
bers, a second chair seat frame bracket rotatably
journaled on the second end of said support tube,
25 said torsion bar having its first end extended through
said first seat frame bracket in freely rotatable rela-
tion and exposed therebeyond,
and a tension arm connected at one end to the first end
30 of said torsion bar to retain said first chair seat
frame bracket on said support tube and having ad-

5

10

15

20

25

30

justable means connected to its other end to abut
said first chair seat frame bracket.

6. In a tilting chair iron,
a hollow elongated support member having first and
second ends,
means mounting said support member to a chair base,
a stop bracket fixed on the first end of said support
member and provided with two spaced abutments,
a first chair seat frame bracket rotatably journaled on
the first end of said support member and alternately
engageable with said two spaced abutments,
a second chair seat frame bracket rotatably journaled
on the second end of said support member,
a torsion bar within said hollow support member and
fixedly connected at one point to said support mem-
ber, said torsion bar having one end extending out
of said support member,
an arm secured at its one end to said extending end
of said torsion bar and having adjusting means con-
nected to its other end to abut the first chair seat
frame bracket,
and said arm being releasably secured to said torsion
bar at a point spaced from the connection point of
said torsion bar to said support member.
